LEO RITTER, OF BROOKLYN, NEW YORK.

FILING SYSTEM.

Application filed November 13, 1925. Serial No. 68,748.

This invention relates to filing systems and aims to provide such a system in which each individual element filed is readily distinguishable without reference either to its 5 position in the file or markings on its face.

In filing systems heretofore used, the distinctive characteristics of the elements filed have been indicated principally by the position of the elements in the file. Such systems necessarily involve the use of guides inserted at frequent intervals in the file. In order to make it possible to locate any element quickly, a considerable number of such guides are necessary, and in the case 10 of an incomplete or changing series of filed elements, a large part of the guide cards may be in use only a part of the time, and during the rest of the time occupy valuable space in the file and interfere with, rather 15 than help in, its use. A more serious disadvantage of such system lies in the fact that an element which is misfiled is completely lost, and that an element cannot easily be located in a mass of elements which 20 have been removed from the file during its use.

In accordance with the present invention, these disadvantages are eliminated and new advantages are gained by providing each 25 individual filed element with a projecting tab which indicates its identifying characteristics. This not only eliminates the necessity for looking at the faces of the elements, the necessity for all guide cards, and 30 the danger of misfiling, but also makes it possible to identify any individual element in a confused mass of elements or to select 35 any element from the file by an identifying characteristic of a sort other than that in 40 accordance with which it is filed.

A filing system embodying the invention in the form which I consider most desirable includes a set of elements provided with 45 tabs of different shapes so arranged that the shape of the tab of each element indicates an identifying characteristic of that element in accordance with a uniform prearranged plan. A further feature of the invention consists in indicating two different 50 sorts of characteristics in each individual element by a single tab on that element by using the position of the tab to represent a characteristic of one sort and the shape of the tab to represent a characteristic 55 of another sort. A characteristic of still

a third sort may be indicated by the color of the tab or of the whole element.

The invention may be applied to many different kinds of filing systems, since identifying characteristics of any sort may be 60 indicated by the shape of the tabs as well as by their position and their color. Thus the invention may be applied to an alphabetical filing system by making the shapes of the tabs indicate letters or parts of the 65 alphabet corresponding to surnames on the elements, while the position of the tabs may indicate the position in the alphabet of first names or initials appearing on the elements. Or again, the shapes of the tabs may indicate 70 sections of the alphabet and the position of the tabs may indicate particular letters or groups of letters in such sections.

A simple application of the invention is 75 to a numerical filing system. In this case three digits of numbers identifying the elements may be indicated separately by the position, shape and color of the tabs so that any one of one thousand elements may be 80 readily identified regardless of its position in the file.

In order to illustrate the use of the invention, I will describe in detail a numerical filing system embodying it which is illustrated in the accompanying drawings:— 85

Fig. 1 is a perspective view, partly broken away, of such a numerical file;

Fig. 2 is a key to the position of the tabs on the elements shown in Fig. 1;

Fig. 3 is a key to the shapes of the tabs; 90

Fig. 4 is a key to the colors of the tabs or elements;

Fig. 5 is a perspective view of a number of individual elements which have been removed from the file shown in Fig. 1 and 95 mixed together; and

Fig. 6 is a perspective view of part of a file in which some of the elements shown in Fig. 1 are arranged according to dates.

The filing system illustrated in Fig. 1, when complete, may include 999 individual elements identified by serial numbers and arranged one behind another in a file case. The individual elements are shown as cards, although it will readily be understood that they may consist of sheets, folders or any other elements capable of being filed. Each element is provided at some point of its edge with a tab.

The word "tab" is used to indicate any 110

projection beyond the face of the element whether or not it be made integral with the rest of the element.

The number of each element is ordinarily marked on its face as shown in connection with the front element in Fig. 5. The numbers may also be marked on the tabs of the elements as shown in Figs. 1, 5 and 6, but this is not essential.

10 The tabs of the various elements occupy ten different positions along the upper edges of the elements which may be termed positions 1, 2, 3, etc., up to 0, numbering from the left, as indicated by the key in Fig. 2. The tab of each element occupies the one of these positions corresponding to one of the digits of the number identifying that element. In the form illustrated, the positions of the tabs indicate the unit digits 15 so that when the elements are aligned, all those identified by numbers terminating in the same unit digit have their tabs directly in line one behind another.

20 The tabs of the various elements are of 25 different shapes. In the embodiment illustrated, ten different shapes are used, arbitrarily representing the digits from 1 to 0 in accordance with the key shown in Fig. 3. The tab of each element has the shape indicating one of the digits of the number identifying that element, for example, the tens digit, so that all elements with identifying numbers having the same tens digit have 30 tabs of the same shape.

35 The elements and tabs are of ten different colors which are chosen arbitrarily to represent the digits from 1 to 0 in accordance with the key shown in Fig. 4. The color of the tab of each element is used to indicate one of the digits of the number identifying that element, for example, the hundreds digit, so that all the elements identified by numbers having the same hundreds digit are the same color.

40 In using the filing system illustrated in Fig. 1 an element identified by any number from 1 to 999 may readily be selected. If, for example, the number sought is 123, it is necessary only to glance at the aligned 45 tabs in the 3 position and to lift the blue two-pointed tab.

50 The misfiling of an element is readily apparent from the failure of its tab to correspond in shape, or to succeed in position, the 55 tabs of the elements adjacent to it. Thus, the elements 15 and 135 are obviously misfiled in the file shown in Fig. 1.

55 It is not essential that the elements be arranged in the file in accordance with the 60 numbers indicated by their tabs as shown in Fig. 1 in order that any element may be identified and selected. Thus an element identified by any given number may be selected from the elements shown in Fig. 5, 65 which have been removed from the file and

confused together, in the same manner as that in which an element is selected from the file itself and with only slightly less facility. This is of great advantage in cases where it is necessary to remove various elements from the file in the course of its use and to leave them together to be sorted out later. Not only is it easy to find a desired element among those removed, but it is also a simple matter to refile the removed elements since the appearance of each element immediately indicates the position in which it should be inserted in the file shown in Fig. 1.

65 It is often important to file the elements shown in Fig. 1 by some system other than their identifying numbers. Thus, for example, it may be desirable to file them, or some of them, in accordance with dates which they bear and which are not connected in sequence with their numbers. This system of filing is illustrated in Fig. 6. In this figure it appears, as is frequently the case, that comparatively few elements are placed in the part of the file relating to any one specific date. The incompleteness of the series of elements for each date, which would render the use of numerical guide cards between the date guides extremely cumbersome, in no way interferes with the use of the tabs of these elements to arrange them in numerical order so that any desired element may quickly be selected. Furthermore, it is not even essential that the group of elements relating to one specific date be arranged numerically as the tabs provide a ready means for selecting any desired element without such arrangement, and, of course, if no attempt is made to preserve the numerical sequence under each date, the refileing of any element may be effected instantly by merely inserting it anywhere in the group of elements behind the guide card bearing the same date as the element.

70 It should be clearly understood that the invention is by no means limited to the illustrative embodiment which has been described.

75 What I claim is:

1. A filing system comprising a continuous series of elements in which each individual element has a distinctive tab in a distinctive location visually indicating by its appearance and location the position of the 80 element in the series without reference to any indicia thereon.

2. A filing system, comprising elements having different identifying characteristics and tabs of different shapes so arranged that the shape of the tab of each element indicates an identifying characteristic of that element in accordance with a uniform plan.

3. A filing system, comprising elements having identifying characteristics of two 85 90 95 100 105 110 115 120 125 130

sorts and provided with tabs of different shapes and in different positions, all the elements which have a common identifying characteristic of one sort having tabs in the same position and all the elements which have a common identifying characteristic of another sort having tabs of the same shape.

4. A filing system, consisting of elements having tabs of different colors and shapes and in different positions, in which the position of the tab of each element indicates an identifying characteristic of one sort, the shape of the tab indicates an identifying characteristic of another sort, and the color of the tab indicates an identifying characteristic of still another sort, so that all elements having a characteristic of one sort in common have their tabs in the same position, all having the characteristic of another sort in common have tabs of the same shape, and all having a characteristic of a third sort in common have tabs of the same color.

5. A filing system, consisting of elements identified by numbers and each having a tab, in which the tabs of the elements are arranged in ten different positions and are of ten different shapes, the shape and position of the tab of each element indicating respectively two digits of its identifying number.

6. A filing system, consisting of elements identified by numbers and each having a tab, in which the tabs of the elements are of ten different shapes and in ten different positions on the elements, the position of

each tab indicating the unit digit of the number identifying that element, while the shape of the tab indicates the tens digit of the number identifying that element.

7. A filing system, consisting of elements identified by a series of numbers and each having a tab, in which the tabs of the elements are in different positions, have different shapes and different colors, all elements identified by numbers which have the same unit digit having tabs in the same position, all elements identified by numbers which have the same tens digit having tabs of the same shape, and all elements which have numbers of the same hundreds digit having tabs of the same color.

8. A filing system, comprising elements identified by characteristics of two unconnected series, in which the elements are arranged serially in accordance with their characteristics of one of said series, and in which each element is provided with a tab indicating its identifying characteristic of the other series.

9. A filing system, consisting of a series of elements identified by a continuous series of numbers and each having a tab in which the tabs of the elements are arranged in different positions and are of different colors, the color and position of the tab of each element indicating respectively two digits of its identifying number.

In testimony whereof I have hereunto set my hand.

LEO RITTER.
